(57) **CLAIM**

The ornamental design for an asymmetric lift mechanism as shown and described.

DESCRIPTION

FIG. 1 is a front perspective view of an asymmetric lift mechanism;

FIG. 2 is a back perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines in the drawings represent portions of the asymmetric lift mechanism that form no part of the claim.

1 Claim, 8 Drawing Sheets
